(57) **CLAIM**

The ornamental design for a mood indicating device, as shown and described.

DESCRIPTION

FIG. 1 is a front elevational view of a mood indicating device showing my new design;

FIG. 2 is a rear elevational view thereof;

FIG. 3 is a side elevational view thereof;

FIG. 4 is a top plan view thereof; and,

FIG. 5 is a bottom view thereof.

The broken lines are for illustration only and form no part of the claimed design.
